DESIGN FOR AN AIRPLANE

Vincent J. Burnelli, Keyport, N. J.

Application October 7, 1942, Serial No. 108,453

Term of patent 14 years

To all whom it may concern:

Be it known that I, Vincent J. Burnelli, a citizen of the United States, residing at Keyport, in the county of Monmouth and State of New Jersey, have invented a new, original, and ornamental Design for Airplanes, of which the following is a specification, reference being had to the accompanying drawings, forming part thereof.

Figure 1 is a top perspective view of an airplane according to my design.

Figure 2 is a top plan view thereof,
Figure 3 is a front elevational view, and
Figure 4 is a bottom plan view.

I claim:

The ornamental design for an airplane, as shown.

VINCENT J. BURNELLI.
